United States Patent Office

Des. 226,566
Patented Mar. 27, 1973

226,566

SUBSCRIBER TERMINAL CONSOLE

Peter P. Klepa and Thomas J. Hermann, Los Angeles,
Calif., assignors to Hughes Aircraft Company, Culver
City, Calif.

Filed July 6, 1971, Ser. No. 160,267

Term of patent 7 years

Int. Cl. D14—02

U.S. Cl. D26—5 C

Fig. 1.

Fig. 2.

Fig. 3.

Fig. 4.

Fig. 5.

Fig. 6.

FIG. 1 is a perspective view of a subscriber terminal console showing our new design;

FIG. 2 is a rear elevational view thereof;

FIG. 3 is a top plan view thereof;

FIG. 4 is a left end elevational view thereof;

FIG. 5 is a right end elevational view thereof; and

FIG. 6 is a front elevational view thereof.

We claim:

The ornamental design for a subscriber terminal console, substantially as shown.
